UNITED STATES PATENT OFFICE.

ALEXANDER WINSLOW, OF WINONA, MINNESOTA.

PHONOGRAPH.

1,318,193.

Specification of Letters Patent.

Patented Oct. 7, 1919.

Application filed November 28, 1917. Serial No. 204,361.

To all whom it may concern:

Be it known that I, ALEXANDER WINSLOW, a citizen of the United States, residing at Winona, in the county of Winona and State of Minnesota, have invented certain new and useful Improvements in Phonographs, of which the following is a specification.

This invention relates to phonographs and the invention has for its object to provide an improved table type of phonograph wherein a phonograph mechanism is received by the table and when desired, can be moved from its operative position, thus giving the article of furniture the appearance of an ordinary table.

Another and equally important object of the invention is to provide a device of the character mentioned in which the phonograph mechanism is rigidly supported when in operative position, thus preventing vibration and the resultant interference with the proper functioning of the sound reproducing means.

Other objects will be in part obvious and in part pointed out hereinafter.

The invention consists, furthermore, in the novel arrangement and combination of parts of the device, as well as in the details of the construction of the same, all of which will be more fully described in the following specification, and then finally embodied in the clauses of the claims, which are appended to the specification and which form an essential part of the same.

The invention is clearly illustrated in the accompanying drawings, in which:—

Figure 1 is a vertical section through the device, and

Fig. 2 is a top plan of the same with the cover open.

Having more particular reference to the drawings and in connection with which like reference characters will designate corresponding parts in the several views, the numeral 1 represents the table in its entirety, the top 2 of which is provided with an opening having the sides thereof rabbeted as at 3, whereby a hinged closure 4 may be received over the same, at times.

An opening 5 is formed in one end of the table 1 and if desired, may be covered by suitable scroll or other ornamental design.

Communicating with the opening 5 is the outer end of a megaphone or phonograph horn 6, the same being preferably formed of wood and supported upon the under side of

the table top through the medium of a bracket or support 7. In this connection, it is to be noted that the fixed or inner end of the megaphone 6 is provided with a resilient packing 8, such as felt washers or the like.

Oppositely disposed supporting bars 9 are secured to the under side of the table top 2 at points adjacent the sides of the opening therein, one of the said bars serving as means for permitting the securing of spring tension hinges 10 thereto, which hinges in turn, are engaged with the adjacent ends of a phonograph mechanism supporting board 11. Slidably mounted on the opposite end of the board 11 is a spring pressed bolt 12, the free end of which is adapted to be engaged in a recess or other suitable form of keeper 13 formed in the adjacent face of the cross bar 9.

The usual motor 14 is supported upon the under side of the board 11 while a turn table 15 is arranged upon the upper side thereof and is directly engaged with the power shaft of the motor 14. A tone arm 16 is arranged on the board and is adapted to have the sound reproducing means 17 thereof engaged with a record arranged on the turn table 15. As will be noted, the free end of the tone arm extends through and below the supporting board 11 and has suitable packing 18 arranged upon its outer end, similar to the packing 8. By reason of the positioning of the outer end of the tone arm 16, the same will align with the inner or constricted end of the megaphone 6, at times, namely, when the phonograph mechanism is arranged in its opposite position. Obviously, due to the engagement of the packing 8 and 18, an efficient jointure between the tone arm 16 and the megaphone 6 will be effected, thereby eliminating vibration and permitting proper functioning of the sound reproducing means 17.

Further, due to the fact that the supporting board 11 is provided with spring tension hinges 10, vibration due to rattling of the board will be prevented. Further, the board will be positively locked when in its raised or operative position, due to the engagement of the spring pressed slideable bolt 12 with the keeper 13 formed in the cross arm 9.

Arranged upon the under side of the hinged closure 4 is a trip arm 19, the same being so positioned as to engage the inner or handle portion of the slideable bolt 12 upon the closing of the same. Thus, it will be

readily understood that to move the phonograph mechanism together with its supporting board 11 to inoperative position, it is only necessary to move the closure 4 from 5 open position inwardly, whereupon the arm 19 will engage the handle portion of the bolt 12, thereby disengaging the same from the keeper 13 and allowing the supporting board 11 to be moved downwardly into its inoperative position. The table 1 has a cross piece B which is conventional with ordinary table structures and this piece serves as a stop and rest for the lower extremity of the tone arm 16 when the supporting board 15 is in lowered position thereby limiting the lowering movement of said board.

To maintain the closure 4 in lower position a bolt 20 is slidably mounted in the table top 2 and is adapted to be engaged with 20 a keeper formed in the free end of said closure.

From the foregoing, it will be appreciated by persons skilled in the art that I have provided an exceedingly simple and efficient 25 table type of phonograph and further, a construction in which all vibration will be eliminated, thereby insuring perfect functioning of the sound reproducing means of the phonograph mechanism, which if permitted, would conflict with the vibration of the reproducer diaphragm. Further, the use 30 of carriages, guides, rails or counter-balances is also eliminated.

Manifestly, the construction shown is capable of considerable modification and such 35 modification as is within the scope of my claims, I consider within the spirit of my invention.

I claim:—

40 1. In a table having an opening in its top, supporting means hinged to the table beneath said opening, phonograph mechanism on the supporting means, a horn supported on the table and adapted to aline with the 45 tone arm of said phonograph mechanism, at times, and a closure for the opening.

2. In a table having an opening in its top, supporting means hinged to the table beneath said opening, phonograph mechanism 50 carried by said supporting means, a horn

rigidly supported on the table and having packing means arranged on its inner end, said horn being adapted to aline with the adjacent end of the tone arm of said phonograph mechanism, at times, and a slidable 55 closure for the opening.

3. In a table having an opening in its top, supporting means hinged to the table beneath said opening, phonograph mechanism carried by said supporting means, a closure 60 for the opening in the table top, locking means arranged on the supporting means for securing the same in operative position, means carried by said closure engageable with said locking means for releasing the 65 same, and a horn rigidly secured to the table and adapted to aline with the tone arm of said phonograph mechanism, at times.

4. In a table having an opening in its top, a supporting board hinged to the table beneath said opening, means for normally maintaining the board in raised position, phonograph mechanism including a tone arm having a laterally distended portion arranged on said supporting board, the outer 75 end of said tone arm being provided with packing, a horn rigidly secured to the table and having packing arranged upon its inner end adapted to aline with the adjacent end of the tone arm, at times, and a closure for 80 said opening having its top surface arranged flush with the table top.

5. In a table having an opening in its top, a supporting board hinged to the table beneath said opening, spring means for normally maintaining said board in raised position, locking means carried by said board and engageable with the table, a closure for 85 said opening, means carried by said closure engageable with the locking means for releasing the same, phonograph mechanism carried by said supporting board including a tone arm having a laterally extended portion, a horn rigidly secured to the table, 90 said horn being adapted to aline with the laterally distended portion of the tone arm, at times.

In testimony whereof I affix my signature hereto.

ALEXANDER WINSLOW.
